UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL COMPOSING-MACHINE.

1,380,807.

Specification of Letters Patent.

Patented June 7, 1921.

Original application filed May 22, 1916, Serial No. 99,059. Divided and this application filed March 19, 1919. Serial No. 283,520.

To all whom it may concern:

Be it known that I, DAVID S. KENNEDY, a citizen of the United States, residing at Brooklyn, in the county of Kings and State 5 of New York, have invented certain new and useful Improvements in Typographical Composing-Machines, of which the following is a specification, reference being had therein to the accompanying drawing, being a division of original application filed May 22, 10 1916, Ser. No. 99,059.

My invention relates to typographical machines, such as linotype machines of the general organization represented in Letters Patent 15 of the United States to O. Mergenthaler, No. 436,532, wherein circulating matrices under the action of escapements are released from a magazine in the order in which their characters are to appear in 20 print and then assembled in line, the line transferred to the face of a mold, the mold filled with molten metal to form a slug or linotype against the matrices which produce the type characters thereon, and the matrices 25 thereafter elevated and returned through a distributing mechanism to the magazine from which they started.

The present invention is directed to certain improvements in the escapement operating devices, as will be more fully pointed out in the detailed description to follow.

In the accompanying drawing, for the sake of simplicity, I have shown my improvements in connection with a single magazine only, although it is my purpose to embody them in a machine equipped with a plurality of magazines which are movably arranged in such manner that any selected one thereof may be brought into operative 30 position at will, such for instance as illustrated in my pending application Serial No. 99,059, filed May 22, 1916, of which the present application is a division. It should be understood, however, that the invention may 35 be embodied in any class of machine to which it is applicable. In addition, I have shown my invention only in preferred form and by way of example, and obviously many changes and variations may be made therein 40 and in its mode of application which will still be comprised within its spirit. Generally speaking, I desire it to be understood that I do not limit myself to any specific 45

form or embodiment except in so far as such limitations are specified in the claims. 55

The drawing is an enlarged vertical section taken through the escapement operating devices and the magazine with which they coöperate.

The matrices X are stored in the magazine 60 A and pass therefrom into the assembler entrance C under the action of the escapements M mounted in the supporting frame M¹. The frame M¹ is provided with a series of sliding plungers N¹ by means of 65 which the escapements are rocked in one direction to release the matrices against the action of springs M² which tend constantly to rock them in the opposite direction. These plungers are actuated by a series or bank of levers N pivoted as at N² 70 to a fixed part of the machine frame and operated by vertically movable reeds N⁵ reciprocated by power-driven mechanism under the control of the keyboard, all in the usual way. Heretofore, and as shown in my prior Letters Patent No. 1,104,512 the actuating levers for the escapement plungers have been made in substantially L-shape 75 form and have had their pivots located well 80 to the rear of the forward ends of the magazines. In this old arrangement, the parts were subjected to considerable wear as a consequence of the sliding or wiping engagement between the levers and the plungers, 85 as well as between the levers and the operating reeds, occurring at each operation. It is the object of the present invention to avoid this objectionable wear, and to that end I have modified the form and arrangement 90 of the parts in such manner as to reduce the friction to a minimum.

As shown, the actuating levers N are of considerable length and practically straight throughout and have their pivotal points located in an inclined plane disposed substantially at right angles to the magazine, (and consequently at right angles to the escapement plungers N¹) and passing through the point of engagement of the actuating levers with the escapement plungers. 95 As a result of this arrangement, when the actuating levers are rocked about their pivots, (as shown by the dotted lines) their upper ends will describe an arc to which the 100 longitudes of the escapement plungers are 105

tangent, and the circular measure of such arc will be substantially equal to the sine of the angle of rotation; or more generally speaking, the upper ends of the actuating 5 levers will move practically in a straight line which coincides with the longitudinal axes of the escapement plungers, thereby avoiding any appreciable sliding or wiping engagement between these parts. The levers N^1 are slightly offset near their middle, as at N^3 , to avoid interference with the vertical movement of the magazine and are formed at such points with notches or recesses N^4 wherein the upper ends of the 10 reeds N^5 engage. The reeds are mounted in a shiftable guide, so that when raised to operate the actuating levers, they may move with the levers, rocking about their lower ends as a pivot, it being noted that the upper 15 ends of the reeds are rounded to avoid any binding. The interlocking of the reeds and actuating levers in this manner avoids any sliding or wiping engagement between the parts when operated.

20 25 As before stated, I have shown my improvements merely in their preferred form and by way of example, and as applied to a particular kind of machine, but obviously many modifications and alterations therein 30 and in their mode of application will suggest themselves to those skilled in the art without departure from its scope.

Having thus described my invention, its 35 construction and mode of operation, what I claim and desire to secure by Letters Patent of the United States is as follows:

1. In a typographical composing machine, the combination of a matrix-releasing escapement, and operating means therefor, 40 the said means including a sliding plunger connected to the escapement, and a pivoted actuating lever of relatively great length

and arranged with its upper end in position to engage said plunger and having its pivotal point located in a plane extending substantially at right angles to the plunger and passing through the point of engagement of the lever with the plunger, said pivotal point being positioned a relatively remote distance from the escapement-plunger so that in the 45 pivotal motions of the lever, its upper end will describe an arc to which the longitude of the plunger is tangent, and the circular measure of which arc will be substantially equal to the sine of the angle of rotation, 50 whereby wear from sliding of the lever on the plunger is prevented.

2. In a typographical machine, the combination of a magazine, a series of escapements therefor, and means for operating 60 the escapements, the said means including sliding plungers connected to the escapements, actuating levers arranged with their upper ends in position to engage the plungers, and devices to operate the actuating 65 levers, the said devices being shiftably mounted and interlocked at their upper ends with the actuating levers so as to rock therewith.

3. In a typographical machine, the combination of a magazine, a series of escapements therefor, and means for operating the escapements, the said means comprising a series of operating devices and an intermediate series of pivoted levers through which the movement of the operating devices is imparted to the escapements, the said devices being shiftably arranged and interlocked at their upper ends with the pivoted levers so as to rock therewith. 75 80

In testimony whereof, I have affixed my signature hereto.

DAVID S. KENNEDY.
